MACHINE TOOL GUARDS

Donald L. Mapson, Los Angeles, Calif., assignor to
M & D Display Mfg. Corporation, a corporation of
California

Application July 21, 1951, Serial No. 237,859

6 Claims. (Cl. 74—612)

This invention relates to guards for protecting the operators of machine tools from injury, and it is a broad object of the present invention to provide a novel and useful guard for this purpose.

While the guard of my invention is broadly applicable to protecting the operators of various kinds of machine tools from injury, it is particularly useful for this purpose when associated with a punch press. The necessity for manually feeding the work to and from the punch and die mechanism in a punch press subjects the operator to the hazard of suffering serious hand injuries unless he is very careful. Among the measures devised to protect punch press operators from such injuries are adjustable guards which are designed to be affixed to the press so as to be disposed between the operator and the punch-die mechanism and which permit the operator a sufficient degree of visibility for him to observe the die mechanism in operation, but exclude the operator's hand from access to the latter while he is feeding the work to and from the same.

In many safety code jurisdictions, regulations have been issued requiring the use of one or the other of various types of punch press guards in connection with the operation of punch presses in that jurisdiction. These regulations have heretofore proved ineffective for one or both of two reasons. Either the guard in question interfered too much with the operator's feeding the press or too much time was lost in affixing it to the press, in removing it, or in re-adjusting it to fit different punch-die mechanisms, it being not infrequently necessary to change the latter several times a day in the course of operating a given press.

It is another object of the present invention to provide a relatively simple and inexpensive punch press guard which may be quickly adjusted to conform to the varied shapes of different punch-die mechanisms, and which may be readily affixed to or removed from a punch press without disturbing the existing adjustment of the guard.

It is another object of the invention to provide such a punch press guard which is adapted for manufacture in a given size which, without any alterations thereof, will fit any of a group of punch presses, the frames of which vary substantially in width.

The manner of accomplishing the foregoing objects as well as further objects and advantages will be made manifest in the following description taken in connection with the accompanying drawings, in which:

Fig. 1 is a perspective view of a preferred embodiment of the invention applied to a punch press and adjusted to fit a particular punch-die mechanism with which said press is equipped.

Fig. 2 is an enlarged fragmentary perspective view of an upper end portion of one of the picket rods of the invention and two of the wire clips employed in supporting these rods on the platform of the invention, one of these clips being shown in place in the uppermost of a series of annular grooves formed in said rod, while the other of said clips is positioned in the plane of another of said grooves as when being moved towards said rod to snap said clip into the latter groove.

2

Fig. 3 is a perspective view of one of a pair of lug brackets employed in mounting the guard of my invention on a press.

Fig. 4 is a plan view of the guard shown in Fig. 1 with most of the rods removed therefrom, the press on which said guard is mounted being shown in section on the line 4—4 of Fig. 1.

Fig. 5 is an enlarged diagrammatic vertical sectional view taken on the line 5—5 of Fig. 4 and illustrating the guard of my invention with the platform thereof disposed horizontally and the rods thereof vertically as when said guard is supported on said brackets on said press.

Fig. 6 is a view similar to Fig. 5 and illustrates the guard of my invention tilted as when applying said guard to said press or when removing said guard therefrom.

Fig. 7 is an enlarged horizontal fragmentary sectional view taken on the line 7—7 of Fig. 5 and showing one of the wire clips of the invention slipped in place in an annular groove on one of said rods.

Fig. 8 is an enlarged fragmentary vertical sectional view taken on the line 8—8 of Fig. 4 and illustrating the construction of one of the spacers by which the main plates of said platform are assembled rigidly in fixed spaced relation.

Referring specifically to the drawings, the invention is therein shown as associated with a punch press 10 having a rockable frame 11 including frame side members 12 which are united by a bolster plate bed 13 on which is bolted a bolster plate 14. The frame 11 is pivotally mounted, in a manner well known in the art on a frame base (not shown). The frame 11 is normally set to support the bolster plate 14 in horizontal position but may be released, rocked on said base and reset to vary the angular disposition of the bolster plate 14 relative to horizontal.

The front faces 15 of the members 12 have recesses 16 formed therein, inner edges of which are beveled and which receive beveled guides 17 which are secured to the members 12 by screws 18 to form V-shaped slideways 19 which slidably receive similarly shaped vertical lands 20 which extend laterally from a crosshead 21 of a ram 22.

The crosshead 21 has a clamp recess 30 formed therein for receiving a clamp block 31. The crosshead 21 and block 31 are semi-cylindrically recessed to receive a cylindrical punch 32 therebetween. Capscrews 33 secure the block 31 to the crosshead 21 and when tightened cause the punch 32 to be tightly clamped in a given vertical relation with the ram 22. The crosshead 21 is also provided with laterally extending vertically apertured bosses 34.

Suitable power mechanism (not shown) is mounted 50 on the upper end of the rockable frame 11 for vertically reciprocating the crosshead 21, this mechanism being under the control of the operator by the manipulation of a foot pedal (not shown) in a manner well known in the art.

The bolster plate 14 is equipped with one or more clamps 35 which are secured to the bolster plate by capscrews 36. These clamps are for the purpose of precisely locating a die 37 on the bolster plate 14 so that this will be in alignment with the punch 32 the lower end of which is shaped to cooperate with the die in a given punch press operation. For maintaining alignment between the die and the punch, the die may be equipped with guide shafts 38 which slide in collars 39 provided on a plate 40 which is rigidly secured to the ram 22.

The preferred embodiment of the invention illustrated 65 in the drawings comprises a punch press guard 50 which is shown as when adapted to a press operation in which the work is fed to the punch press 10 along a path indicated by the arrow A in Fig. 1. When thus fed, the work generally continues intermittently through the press and out therefrom along the path indicated by the arrow B in Fig. 1.

The guard 50 includes a pair of brackets 51, a platform 52 and a multiplicity of picket rods 53.

The brackets 51 are secured as by capscrews 54 to the front faces 15 of the punch press frame side members 12. Bent forwardly from outer side edges of the brackets 51 are arms 55 which have lugs 56 extending upwardly and at a slightly rearward inclination therefrom. The lugs 56 are set back slightly from the front ends of arms 55 to form shoulders 57 which are in horizontal alignment with upper edges 58 of the arms 55.

The platform 52 is preferably of fabricated construction as shown in the drawings and is made up of a pair of identical plates 65 and 66 which are joined together by solid spacer columns 67. Pins 68 extend axially from upper and lower ends of said columns, and through aligned holes 69 in the plates 65 and 66, these being then peened down to unite the plates 65 and 66 in rigid parallel spaced relation as shown in Figs. 1, 5, 6 and 8.

The outline of the platform 52 is such that, when held parallel with the bolster plate 14 and at the same distance therefrom as the brackets 51, this platform will fit around the ram 22 as shown in Fig. 4. To accomplish this, a recess 68 is formed in the rear edge of the platform 52 to conform to vertical upward projections of the bosses 34, a central recess 69 also being provided which conforms to the clamp block 31 of the ram 22. The upper faces of the bosses 34 are normally disposed slightly below the level of the platform 52. The recess 68 is nevertheless shaped as shown in Fig. 4 to accommodate bolts and nuts which are associated with the bosses 34 when the latter are employed in mounting a plate 40 on the ram 22.

The plates 65 and 66 are provided with like sets of perforations 69 and 70 which are aligned respectively with each other to furnish the platform 52 with a mass of holes 71 the axes of which are normal to the plane of the platform. These holes are of a size to slidably receive the rods 53 as shown in Figs. 1, 5 and 6. There are a great many more holes 71 in the platform 72 than there are rods 73, the reason for this being made clear hereinafter.

The plates 65 and 66 are also provided with like perforations 75 and 76 which are aligned respectively with each other to provide a row of slots 77 adjacent to and parallel with the rear edges of opposite end portions of the platform 52. The slots 77 are for use in mounting the platform 52 upon the brackets 51.

Frame members 12 of the punch press 10 are spaced apart such a distance that when the brackets 51 are affixed to these members as shown in this view, the lugs 56 are spaced apart the same distances as the innermost pair of slots 77. Being slightly longer than the lugs 56 are wide, slots 77 readily receive these lugs when the platform is given a tilted position as shown in Fig. 6 and lowered until the rear edge of the plate 66 of the platform comes to rest on the upper edges 58 of the bracket arms 55. The platform 52 may now be released whereupon it will rock downward to a horizontal position of rest as shown in Fig. 5, with the rear edges of the perforations 75 and the front edges of the perforations 76 of the innermost pair of slots 77 engaging the lugs 56, and with the lower plate 66 resting on the upper edges 58 and shoulders 57 of the arms 55.

When it is desired to remove the platform 52 from this horizontal position of rest (Figs. 1 and 5), the platform is merely tilted, as shown in Fig. 6, and lifted in order to enable the operator to readily remove it from the punch press.

The picket rods 53 are preferably cylindrical in form and have a series of equally spaced annular detent grooves 80 formed in the upper half of their length which grooves are adapted to selectively receive spring wire clips 81 which are of U-shaped formation with flaring tips 82 and outbent detent sections 83. Any of the clips 81 is adapted to be expanded by pressing the flaring tips 82 thereof into opposite sides of one of the annular grooves 80 of each of the picket rods 53 with the result that this clip will

snap into place in said groove with the detent sections 83 of this clip gripping this rod 53 and holding the clip assembled with the rod as shown in Fig. 7. Thus when each rod is inserted downwardly through one of the holes 71 in the platform 52 its downward movement will be halted when the clip 81 thereon engages the upper surface of the plate 65 of this platform as shown in Figs. 1, 5 and 6. The grooves 80 and clips 81 thus provide a means for limiting the downward gravitation of the rods 53 through the holes 71 and for supporting these rods on the platform 52 at a predetermined position in these holes when the platform 52 is lifted so as to transport the guard 50 from place to place.

Operation

In preparing the guard 50 for use in guarding a punch press 10 with a new die 37 set up on the bolster plate 14, such of the rods 53 as are located in holes 71 of the platform 52 which would engage this die and block the assembly of the platform 52 on the brackets 51 as above described, are removed from said holes after which the platform 52 is so assembled on the brackets 51. The picket rods thus removed are then inserted in other holes 71 to form a picket wall 90 which conforms to the front outline in plan of the die 37 as closely as permitted by the limitations of the pattern in which the holes 71 are formed in the platform 52. The picket wall 90 is also preferably extended inwardly at its ends over the paths A and B along which the work is fed to and from the die 37.

It is preferable that all of the rods 53 be provided with clips 81 so as to prevent any of these rods from dropping downwardly through its hole 71 when the platform 52 is lifted as when removing the guard 50 from the punch press 10.

It is also preferable, in using the guard 50, to select a groove 80 in which to insert a clip 81 on each of the rods 53 which will support that rod on the platform 52 when the guard 50 is assembled on the punch press 10 as shown in Fig. 1. The grooves 80 are uniformly spaced apart on the rods 53 a distance which it is allowable for the lower ends of the rods 53 to be spaced above the bolster plate 14 and various portions of the die 37 without the guard 50 failing in its function of offering a barrier to the accidental introduction of the fingers of the operator through the picket wall 90 a sufficient distance to cause injury.

The reason for alternate pairs of slots 77 being provided in the platform 52 is to adapt a single guard 50 to its being optionally employed with any of several different sizes of punch presses varying in width. The latter variations result in changes in the horizontal spacing of the brackets 51 and alternate pairs of slots 77 are spaced so as to accommodate the lugs 56 in each of the various spacings of the brackets 51.

It is to be understood that the fabricated structure for the platform 52 is preferred because of its cheapness and lightness and that where material is available for the platform 52 which is sufficiently light and inexpensive to warrant this platform being made in solid form the latter would be entirely satisfactory.

It is also to be noted that the grooves 80 and spring clips 81 constitute a detent means which is only one of many different forms of such a means which might be provided for selectively limiting the gravitation of the rods 53 downwardly through the platform holes 71.

The claims are:

1. In a machine tool guard, the combination of: a plurality of picket rods sufficient in number to form a picket barrier conforming to a given boundary outline of a danger zone, said boundary outline being substantially variable in shape for different operations to be performed by said machine tool; and a platform, mounted when in use on said tool and over said danger zone, said platform having a mass of closely spaced rows of holes, into any

5

suitable selected series of which holes said rods may be inserted to unite said rods in such a barrier, which will conform to any one of a variety of danger zone boundary shapes.

2. In a guard for a punch press having a bolster plate, vertical side frame members thereabove, and a ram located between said members and mounted for vertical reciprocation relative to said bolster plate and said members, the combination of: brackets applied when in use to said side frame members adjacent a level above the uppermost position of the lower end of said ram; a platform adapted to be supported on said brackets, said platform being shaped to conform to the front and side portions of said ram and being provided with a mass of closely spaced rows of holes; and a plurality of picket rods inserted, when in use, in any suitable selected series of said holes whereby said rods are united by said platform to form a picket barrier excluding the operator's hand from a danger zone between the bolster plate and ram.

3. In a guard for a punch press having a bolster plate, vertical side frame members thereabove and a ram located between said members and mounted for vertical reciprocation relative to said bolster plate and said members, the combination of: a platform adapted to be supported on said side frame members substantially parallel with said bolster plate and spaced upwardly therefrom at a level above the uppermost position of the lower end of said ram, said platform being provided with a mass of closely spaced holes, and being shaped to conform substantially to forwardly protruding portions of said ram at said level, so that portions of said platform at opposite ends thereof extend rearwardly close to said side frame members; brackets having lugs and fixed when in use to said side frame members with said lugs extending upwardly, there being vertical apertures in said platforms adapted to receive said lugs to support said platform at said level on said side frame members; a plurality of rods sufficient in number to form a vertical picket barrier disposed in front of said ram and conforming substantially to a punch-die mechanism which may be fixed to and associated with said bolster plate and said ram, said holes in said platform being adapted to receive said rods to assemble the latter in the form of said picket barrier, there being an excess number of said holes permitting a substantial degree of choice in the location and conformation of said well.

4. In a machine tool guard, the combination of: a plurality of picket rods sufficient in number to form a picket barrier conforming to a given boundary of a danger zone, the shape of the outline of which boundary varies substantially in different operations performed by said machine tool, said barrier being disposed between said

6

zone and the machine operator; a platform comprising a pair of closely perforated plates; spacers rigidly uniting said plates with the latter positioned so that corresponding perforations of said plates are in axial alignment with each other, each corresponding pair of perforations forming a hole through said platform, a mass of closely spaced holes thus being provided in said platform into any suitable selected series of which said rods may be extended to unite said rods in such a barrier, in any one of a variety of danger zone boundary outline patterns; and means for mounting said platform substantially horizontally on said tool.

5. In a guard for a machine tool having a danger zone, the outline of a given boundary of which is substantially variable for different operations performed by said tool, the combination of: a platform; means for mounting said platform when in use on said tool with said platform disposed normal to the aforesaid boundary of said danger zone; a plurality of picket rods sufficient in number to form a picket barrier extending along and conforming to said boundary of said danger zone in each of the various shapes which said boundary manifests, said platform being provided with a mass of closely spaced holes into any suitable selected series of which holes said rods may be inserted to unite said rods to form such a barrier, there being such an excess number of said holes provided in said platform over and above the number of said rods required in forming said barrier as to permit said barrier to be made to substantially conform to said boundary of said danger zone in any one of the variety of shapes said boundary manifests in the different operations performed by said machine tool.

6. A combination as in claim 5 in which said picket rods are provided with longitudinally spaced grooves; and a plurality of spring clips one of which is adapted to snap onto each of said rods and fit into one of said grooves on said rod, and come to rest on the upper surface of said platform when said rod is inserted into one of said holes, whereby the distances which said rods extend respectively inwardly from said platform may be selectively determined to cause the inner edge of said barrier to conform substantially to the corresponding edge of said danger zone boundary.
